GUSTAV A. HAGEMANN, OF NATRONA, PENNSYLVANIA.

Letters Patent No. 82,309, dated September 22, 1868.

IMPROVEMENT IN THE MANUFACTURE OF BROMINE FROM BITTERN.

The Schedule referred to in these Letters Patent and making part of the same.

TO ALL WHOM IT MAY CONCERN:

Be it known that I, GUSTAV A. HAGEMANN, a citizen of the Kingdom of Denmark, now resident at Natrona, in the county of Allegheny, and State of Pennsylvania, have invented a new and useful Improvement in the Manufacture of Bromine; and I do hereby declare the following to be a full, clear, and exact description thereof.

My invention is an improvement in the process of extracting bromine from bittern or "mother-water," and, in connection therewith, of an improvement in the apparatus employed for that purpose.

In the accompanying drawing, which forms part of this specification—

Figure 1 is a plan or top view of my improved apparatus, and

Figure 2 is a longitudinal sectional elevation thereof.

In both figures, like letters of reference are employed to denote similar parts of the apparatus.

To enable others skilled in the art to make use of my invention, I will proceed to describe my apparatus, and explain its use and operation.

It is important, in the manufacture of bromine, to avoid the presence of metallic substances in the apparatus employed, because most of the metals are attacked and injuriously affected by the bromine, and also by the muriatic acid which is liberated during the process of extracting bromine from the bittern.

I have also discovered that the use of naked steam, introduced into the vessel containing the mother-water under treatment, effects an important improvement in the process of extracting the bromine, aiding its evaporation, and facilitating as well as materially hastening its elimination, not only by the physical action of the heat employed, but also by its mechanical effect of agitating the particles of the liquor.

My improved apparatus consists of a trough or vessel, A, made of sandstone, and preferably of a single piece. It has a cover, B, also of sandstone, made to fit closely to the top of the vessel A, and, when in use, luted down, so as to prevent the escape of any of the bromine vapor. A hole is bored at or near the bottom of the vessel A, which hole is closed by a plug, D, when the apparatus is in use, and, when the operation is completed; the residual liquor is drawn off by removing the plug D. A hole, C, is bored longitudinally into the bottom of the trough A, from one side or end, extending to a point somewhere about the middle of the vessel, and then turning upwards, so as to communicate with the interior of the trough. The hole C may pass immediately through one of the walls of the trough, instead of extending through the bottom, although the method described and shown in the drawing is preferable, as it admits the steam more centrally. A steam-pipe, c, through which steam passes from a generator into the interior of the trough A, is inserted into or connected with the external orifice of the bore C. In the stone cover B is a small hole, through which is inserted a glass tube, E, long enough to extend a few inches below the surface of the fluid contents of the trough. Through a larger opening in the cover B is inserted a stoneware funnel, the neck of which also dips into the liquor under treatment. A leaden pipe, G, is fitted into the cover B, opening into the trough, and serving as a goose-neck, to carry off the bromine vapors. It terminates in a leaden worm, I, enclosed in a refrigerating-vessel, H. The lower extremity of the worm I, passing out of the refrigerator H, enters a receiver, M, wherein the fluid bromine is collected as it runs from the worm. The joints around the glass pipe E, funnel F, and goose-neck G, in the stone cover B, are luted tight, so as to prevent leakage of bromine vapor.

In order to permit of the escape of any air or uncondensed vapor, a small pipe, d, is inserted into the top of the receiver M, from which it conducts to a smaller vessel, N, where its orifice is sealed by immersion into an alkaline solution. This, however, is not a necessary part of the apparatus.

The operation of extracting bromine from mother-water, by means of the apparatus just described, is as follows:

The stone trough A is first heated by passing steam into it through the pipe c and bore C. The steam may be used at any convenient pressure, and need not be much over 212° Fahrenheit. When the trough has been thoroughly heated, the mother-water or bittern, having been previously concentrated by boiling down, is run into the trough A, through the funnel F, until the vessel is about one-third full.

It is important to know the percentage of bromine contained in the bittern under treatment, as the quan-

tity of other ingredients employed in the process depends on the amount of bromine which is present. This is readily ascertained by analysis. To the bittern in the trough A, I then add, through the funnel F, an amount of sulphuric acid which will be the equivalent of the quantity of bromine known to be in the quantity of mother-water to be treated. The acid is first diluted with about four times its weight of water. The trough is then filled up with mother-water until the mouth of the funnel F is covered with the fluid to the depth of a few inches. I then make a solution of chlorate of potash in water, or a thin paste of black oxide of manganese and water or bittern, and add the solution or the paste (whichever may be used) slowly to the contents of the trough, through the glass tube E, which has a funnel-shaped mouth for that purpose. The quantity of chlorate of potash, or of black oxide of manganese, will depend on the strength of the bromine in the bittern, being such as to be the equivalent of the sulphuric acid. When the liquor in the trough A has been thus prepared, I turn on the live steam through the pipe and bore C, and the heat of the steam rapidly evaporates the bromine, as it vaporizes at about 142° Fahrenheit, much below the steam heat. The steam, as it enters the trough, must force its way through the liquor, and, in so doing, it mixes intimately therewith, and produces a violent agitation of the particles of the fluid, thereby eliminating the bromine more easily and rapidly, and causing it more freely to separate from the water and pass off, than it would do by the mere application of heat without the use of naked steam. As the bromine is eliminated in the form of vapor, it condenses in the worm, and flows thence into the receiver M.

When the bromine ceases to flow, the residual liquor is removed, as before stated, and the process is repeated with a fresh charge.

I am aware that sandstone troughs have been used before in making bromine, but always heated by a metallic pipe, or other metallic device, passing through the trough, so as to come in contact with the bromine and the liquor in the vessel, which not only injures the bromine, but also rapidly destroys that part of the apparatus. These injurious effects are obviated in my apparatus; therefore,

What I claim as my invention, and desire to secure by Letters Patent, is—

1. The use, in the manufacture of bromine, of a sandstone trough or vessel, furnished with a bore, C, for the introduction of steam, so as to dispense with the insertion, into the liquor, of metallic pipes.
2. Also, the use, in the process of extracting bromine from bittern or mother-water, of naked steam, introduced into the body of the liquor under treatment, for the purpose of combining the mechanical action of the steam with the physical effects of its heat, to produce the desired effect.

In testimony whereof, I, the said GUSTAV A. HAGEMANN, have hereunto set my hand.

G. A. HAGEMANN.
